RIBBON-INKING MACHINE.

1,351,582.

Specification of Letters Patent. Patented Aug. 31, 1920.

Application filed September 30, 1919. Serial No. 327,505.

To all whom it may concern:

Be it known that I, HENRY G. MUTSCHLER, a citizen of the United States, and resident of Rochester, in the county of Monroe 5 and State of New York, have invented certain new and useful Improvements in Ribbon-Inking Machines, of which the following is a specification.

The present invention relates to inking machines and more particularly to the type employed for inking ribbons such as those used in typewriting and other record machines. An object of this invention is to provide an inking machine in which the amount of ink fed to the inking mechanism 10 may be effectively controlled by a simple and inexpensive means. Another object of the invention is to provide a construction which is adapted for making bichrome ribbons and which will produce such ribbons properly saturated or coated without any intermingling of the colors. Another object of the invention is to provide between an inking mechanism and the take-up wheel 20 a guide for the ribbon which may be adjusted in such a manner as to eliminate all slack between the take-up wheel and the inking mechanism.

To these and other ends, the invention 30 consists of certain parts and combinations of parts, all of which will be hereinafter described, the novel features being pointed out in the appended claims.

In the drawings:

35 Figure 1 is a side view of a bichrome ribbon inking machine embodying the present invention;

Fig. 2 is a diagrammatic view showing the driving means of the two inking mechanisms and the take-up wheel;

40 Fig. 3 is a section on the line 3—3, Fig. 1 looking toward the right;

Fig. 4 is a horizontal section on the line 4—4, Fig. 1;

45 Fig. 5 is an enlarged view in side elevation of the first acting inking mechanism;

Fig. 6 is a fragmentary sectional view showing one end of the pressure frame co-operating with one of the bearing blocks of 50 an upper roller of each inking mechanism;

Fig. 7 is a fragmentary plan view showing the wipers co-operating with the lower roller of each inking mechanism;

55 Fig. 8 is a fragmentary view partially in section and partially in side elevation show-

ing the wipers co-operating with the lower roller of each inking mechanism;

Fig. 9 is a sectional view through the frame on the line 9—9, Fig. 1;

Fig. 10 is a vertical section on the line 3—3, Fig. 1 looking toward the left;

Fig. 11 is a detail view showing the adjustable ribbon guide between the inking mechanism and the take-up reel; and

Fig. 12 is a detail view of the brake on the end of the shaft of the feed reel.

In the embodiment of the invention herein illustrated 1 indicates two legs of supports which are connected together by two angle bars 2 to form the base of the main frame. On this frame one or more inking mechanisms are mounted together with means for causing an inking ribbon to travel past such inking mechanisms. In this embodiment, two inking mechanisms are arranged on the frame in such a manner as to ink opposite edges of a ribbon fed by the ribbon feeding mechanism, these inking mechanisms operating on the ribbon at two spaced points so that the ribbon has time to absorb ink of one mechanism and the ink has time to set before ink is fed to the ribbon by the other inking mechanism.

In this embodiment of the invention, each inking mechanism is supported on the main frame through two standards 4, said standards being bolted at their lower ends to the angle bars 2 at 5 and being provided with vertical guide slots 6, the upper ends of each pair of standards being connected by a cross piece 7. The inking devices comprise in this instance, two rollers 8 and 9, the roller 8 being arranged above the roller 9 and both rollers each having its shaft mounted to turn in a pair of bearing blocks 10 which are guided in the two standards 4. Ink is fed to each pair of inking rollers 8 and 9 preferably by a feed roller 11 for each pair, such feed roller in this instance being journaled in the standards 4 below the pair of inking rollers so as to co-operate with the lowermost portion of the roller 9. This feed roller preferably turns in an ink pot or receptacle 12 and carries ink therefrom to the lower inking roller 9 which in turn conducts it to the inking ribbon 13 operating between the rollers 8 and 9, the roller 8 tending to squeeze the ink into the inking ribbon.

The operating planes of the two pairs of

rollers 8 and 9 are out of alinement so that one pair will operate on a portion of the ribbon different from that on which the other pair operates, that is, one pair inks 5 substantially one-half of the ribbon while the other pair inks substantially the other half of the ribbon due to the fact that the rollers operate along opposite edges of the ribbon.

- 10 The second pair of inking rollers 8 and 9 are adjustable in the direction of their axes, the purpose of this being to change their operating planes in order that the operating planes may be moved toward or 75 15 from the operating planes of the first named pair of rollers. This adjustment is preferably effected by making the shafts 74 and 75 of said rollers 8 and 9 adjustable axially, said shafts in this instance each having screw 20 threaded portions 76 thereon (see Fig. 4) near each bearing and being provided with nuts 77 engaging said screw threaded portions and also the inner faces of the bearings 10 in which said shafts turn.
- 25 For controlling the amount of ink fed to each pair of rollers 8 and 9 through the feed roller 11, means is provided for adjusting the rollers 8 and 9 with reference to its feeding roller. This means in this instance 90 30 comprises wedge blocks 19 arranged at the lower ends of the slots 6 and movable transversely of said slots through adjusting screws 20, these wedge blocks coöperating with inclined surfaces 21 on the lower bearing blocks 10 35 so that a movement of the wedge blocks 19 transversely of the length of the slots effects the movement of the rollers 8 and 9 in the guide slots 6 and in this way moves the roller 9 toward and from the roller 11 to vary the 40 amount of ink taken up by the roller 9 from the roller 11.

Each roller 8 may be held toward its roller 9 with a yielding pressure and to this end a pressure frame 22 has depending portions 45 23 guided in the upper part of the guides and engaging the upper surfaces of the blocks 10 which support the roller 8. This pressure frame is acted upon by a weight 24 adjustably mounted on an arm 25 which is 50 pivoted at 26 to the cross piece 7 and bears adjacent its pivot in a saddle 27 on the top of the cross bar 22. This pressure means in addition to holding the roller 8 with pressure toward the roller 9, also tends to maintain 55 coöperation between the roller 9 and the roller 11, such coöperation being controlled by the adjustable wedge blocks 19. A screw 22^a carried by the frame 22 serves to co-operate with the cross piece 7 in order to 60 equalize the pressure on the rollers.

The driving of the two inking mechanisms is effected preferably through a pulley 28 on the shaft of one of the feeding rollers 11 and also arranged on this shaft of the feeding 65 roller are a loose pulley 28^a, a hand wheel 3

and a gear 29, the latter meshing with a gear 30 on the shaft of the roller 9 directly above said roller 11. This gear 30 in turn meshes with a gear 31 on the shaft of the roller 8 above the aforesaid roller 9. Also arranged 70 on the shaft of the roller 11 on which the pulley 28 is arranged is a sprocket wheel 32 which by a sprocket chain 33 connects with a sprocket wheel 34 on the shaft of the other roller 11. This shaft of the last mentioned roller 11 has a sprocket wheel 35 thereon and a gear wheel 36. The gear wheel 36 meshes with a gear wheel 37 on the roller 9 directly above the last mentioned feed roller 11 and the gear wheel 37 in turn meshes 80 with a gear wheel 38 on the shaft of the roller 8 coöperating with said roller 9.

It is desirable that excess ink be removed from the end of each lower roller adjacent the portion that operates at the center of the 85 ribbon. To this end a scraping means is provided comprising preferably two scraping blades 14 projecting in opposite directions from a post 15 supported between the ink pots 12 on the main frame. These blades have faces provided with yielding material and coöperate with a lower roller 9 and a feeding roller 11 adjacent the point where the peripheries of these two rollers engage. Each blade has an inner resilient portion 16 which will permit the movement of the yielding portion toward and from the two rollers 9 and 11. Movement of each blade may be effected by a set screw 17 mounted on an arm 18 and engaging with the blade. 100

The uninked tape is held on a drum 39 which has a flange 40 at one side thereof. This drum is secured by a set screw 41 to a shaft 42 that is mounted to turn in a bearing 43 on a bracket 44 projecting upwardly 105 from one of the side bars 2. Also arranged on the shaft 42 is a friction disk 45 with which a friction band 46 engages (see Fig. 12). This friction band prevents the shaft 42 and the drum 39 secured to such shaft from rotating too freely. After leaving the drum 39 the tape passes between two pairs of rollers 8 and 9 and is conducted to a take-up drum or reel 47 which also has a flange 48 at one side thereof. The movement of the tape is effected by driving the reel or drum 47, the latter in this instance being secured by set screws 49 to the shaft 50 which is journaled in a bearing 51 on a bracket 52 projected upwardly from a side bar 2 of the main frame. On the shaft 50 is a sprocket wheel 53 which has slip connection with the shaft preferably through a disk 54 secured to the sprocket and a disk 55 secured to the shaft, a spring 56 acting on the sprocket to 115 hold the disks 54 and 55 in coöperation. The sprocket 53 connects by a chain 57 with the sprocket 35 on the shaft of the adjacent feed roller 11 (see Fig. 2). This slip connection between the sprocket 53 and the 120 125 130

shaft 50 is provided in order that should the tape be held against traveling, then the slip joint will become effective and the breaking of the tape will be prevented.

5 The guiding of the tape adjacent the two pairs of rollers is effected preferably by oppositely disposed guides 58 and 59. These guides have flat surfaces coöperating with the under flat side of the ribbon or tape, the 10 receiving ends of the flat surfaces being turned downwardly. At one side, each guide has an upwardly extending guide flange 60, the guide flanges being on opposite sides in the two guides and lying in the operating planes of the rollers of the other pair. The guides 58 and 59 are each adjustably supported upon a rod 61, said rod being supported at opposite ends in brackets 62 bolted to the standards 4. A set screw 20 63 adjustably secures each guide to its rod 61 so that the guide may be moved transversely of the line of feed of the ribbon in order that its guiding edge may coöperate with one edge of the ribbon.

25 A slack take-up and guide may be arranged between the take-up drum 47 and the second acting inking mechanism. This device is shown in detail and comprises preferably a shaft 64 secured in a bracket 30 65 which projects upwardly from one of the side bars 2, such shaft having thereon a two arm frame 66 which is adjustably secured in different positions on the shaft 64 by a set screw 67. Between the two arms 35 66 a roller 68 is arranged, said roller being supported by adjustable bearings 69 on the two arms and having two adjustable collars 70 thereon between which the ribbon 13 operates, these collars being adjustable so 40 that different widths of ribbons may be accommodated. Owing to the fact that the guide roller 68 is mounted on a frame adapted to swing on the shaft 64, the guide is adapted to swing about an axis for the purpose 45 of taking up slack in the ribbon between the inking mechanism and the take-up drum or reel.

If desired, a paper reel 71 may be mounted on the frame of the machine preferably 50 through an arm 72 secured to a side bar 2 of the main frame. A paper tape 73 leads from this drum to the ribbon take-up drum 47 and is adapted to supply a paper strip to the drum between the convolutions of the 55 ribbon so that any excess ink will be absorbed by the paper strip.

The operation of the invention will be understood from the foregoing description but it may be summarized as follows:

60 An uninked tape on the reel 39 is started through the machine being carried through the two inking mechanisms and connected to the take-up reel 47. The guides 58 and 59 as well as the two pairs of inking rollers 65 are properly adjusted so that one edge of

the ribbon is inked with one color while the opposite edge of the ribbon is inked with another color, the operating planes of the two inking mechanisms being so adjusted that the two colors meet without the intermingling. In passing through each inking mechanism, ink is taken up by the tape from the first lower roller 9 which is fed by the feed roller 11. The upper roller 8 tends to squeeze the ink into the ribbon. After 70 one edge of the ribbon is inked, it passes to the second inking mechanism which acts in a like manner upon the opposite edge. The amount of ink fed to the lower roller 9 of each inking mechanism is controlled by 80 the adjustable wedge 19 which controls the position of the roller 9 with reference to the roller 11, the roller 8 being also moved with such adjustment. The amount of pressure on the ribbon is determined by the 85 adjustable weight 24. Slack in the ribbon between the second acting inking mechanism and the take-up reel is controlled by the combination guide and take-up 68.

From the foregoing it will be seen that 90 there has been provided a bichrome ribbon inking machine in which two inking mechanisms are provided to operate at spaced points on opposite edges of a ribbon fed through the machine, this being preferably 95 effected through two pairs of rollers having their operating planes out of alignment. A ribbon inking machine has also been provided in which a guide controls the passage of the ribbon by the two rollers and has its 100 guiding edge spaced from one of the faces of the rollers. Scraping means has been employed in connection with two pairs of rollers operating along opposite edges of a ribbon at two spaced points so that the rollers are cleared of excess ink at their ends adjacent the center of the ribbon. Means has been provided for varying the amount of 105 ink fed to the inking rollers by adjusting the inking rollers with reference to a feed 110 roller. This adjusting means is of simple construction and is not liable to get out of order. Pressure operating means coöperates in connection with such adjusting means to maintain the desired pressure on the ribbon notwithstanding the different adjustments of the inking rollers with reference to the ink feeding roller.

What I claim as my invention and desire 115 to secure by Letters Patent is:

1. A bichrome ribbon inking machine comprising two inking mechanisms arranged to ink opposite edges of a ribbon fed through the machine, said mechanisms operating on the ribbon at two spaced points, in the direction of the length of the ribbon.

2. A bichrome ribbon inking machine comprising two pairs of rollers between which the ribbon is caused to travel, one pair inking the ribbon along one edge, and

- the other pair inking the ribbon along the other edge, said pairs operating on the ribbon at two spaced points, in the direction of the length of the ribbon.
5. A bichrome ribbon inking machine comprising two pairs of rollers between which the ribbon is caused to travel, one pair inking the ribbon along one edge and the other pair inking the ribbon along the opposite edge, and means for effecting an axial movement of one pair of rollers for the purpose of varying the field of operation of such rollers on the ribbon.
10. 3. A bichrome ribbon inking machine comprising two pairs of rollers between which the ribbon is caused to travel, one pair inking the ribbon along one edge and the other pair inking the ribbon along the opposite edge, and means for effecting an axial movement of one pair of rollers for the purpose of varying the field of operation of such rollers on the ribbon.
15. 4. A bichrome ribbon inking machine comprising two pairs of rollers between which the ribbon is caused to travel, said pairs of rollers operating on the ribbon at two spaced points in the direction of the length of the ribbon and having their active sections out of alinement so that one pair will operate on a portion of the ribbon different from that on which the other pair operates.
20. 5. A bichrome ribbon inking machine comprising two inking mechanisms past which the ribbon is caused to travel, said mechanisms operating on the ribbon at spaced points out of alinement in the direction of the travel of the ribbon so that said mechanisms operate along opposite edges of the ribbon.
25. 6. A bichrome ribbon inking machine comprising two inking mechanisms past which the ribbon is caused to travel, said mechanisms operating on the ribbon at spaced points out of alinement in the direction of the travel of the ribbon so that said mechanisms operate along opposite edges of the ribbon, and means for adjusting one of said mechanisms transversely of the direction of travel of the ribbon.
30. 7. A ribbon inking machine comprising a pair of inking rollers between which the ribbon is caused to travel, and a guide for the longitudinal edge of the ribbon arranged in spaced relation to that face of said pair of rollers, which operates in the plane of the ribbon.
35. 8. A bichrome ribbon inking machine comprising two pairs of rollers between which the ribbon is caused to travel, said rollers operating upon the ribbon at two spaced points and having their active sections out of alinement, and two guides, one for each pair of rollers, the guide of each of said pair of rollers having its guiding edge lying in the plane of operation of the other pair of rollers.
40. 9. A bichrome ribbon inking mechanism comprising two pairs of rollers between which the ribbon is caused to travel, said rollers operating upon the ribbon at two spaced points and having their active sections out of alinement, and two scrapers operating on one roller of each pair at the end
45. of such roller nearer the center of the ribbon.
50. 10. A ribbon inking machine comprising a frame having guides thereon, an ink feeding roller mounted to turn in said frame, a pair of inking rollers having bearing blocks movable on the guides of the frame, the upper roller being free to move toward the lower roller, and means for adjusting the bearing blocks of the lower roller on the guides to cause both rollers to move simultaneously toward and from the feeding roller.
55. 11. A ribbon inking machine comprising a frame having a pair of slotted standards forming guides, an ink feeding roller journaled in the standard below the ends of said guide, a pair of inking rollers having bearing blocks movable on said guides, the upper roller being free to move toward the lower roller, and means for adjusting the bearing blocks of the lower roller on the guides in order to effect the simultaneous movement of both inking rollers toward and from the feeding roller.
60. 12. A ribbon inking machine comprising a feeding roller, a pair of inking rollers having bearing blocks adjustable toward and from the feeding rollers, the upper roller being free to move toward the lower roller and wedge members arranged to effect the movement of the lower bearing blocks on the guides in order to effect a simultaneous movement of both inking rollers toward and from the feeding roller.
65. 13. A ribbon inking machine comprising a frame having a pair of slotted standards forming guides, a feeding roller journaled in the standards below the ends of the guides, a pair of inking rollers having bearing blocks movable on the guides, the upper roller being free to move toward the lower roller and wedge blocks adjustably mounted at the lower ends of the slots to move transversely of the slots in order to effect the movement of the lower bearing blocks on the guides for the purpose of moving both inking rollers toward and from the feeding roller.
70. 14. A ribbon inking machine comprising a frame having a pair of slotted standards forming guides, a feeding roller journaled in the standards below the ends of the guides, a pair of inking rollers having bearing blocks movable on the guides, wedge blocks adjustably mounted at the lower ends of the slots to effect the movement of the bearing blocks on the guides for the purpose of moving the pair of inking rollers toward and from the feeding roller, and means acting on said bearing blocks for the purpose of maintaining said inking rollers in co-operation with the wedge members.
75. 15. A ribbon inking machine comprising a frame having a pair of guides thereon, a

feeding roller mounted to turn on the frame below said guides, two inking rollers each having a pair of bearing blocks movable on the guides, wedge blocks adjustably mounted to coöperate with the bearing blocks of the lower roller for the purpose of adjusting said roller toward and from the feeding roller, and yielding means acting on the bearing blocks of the upper roller for the purpose of holding said upper roller toward the lower inking roller.

16. A ribbon inking machine comprising a frame having a pair of guides thereon, a feeding roller mounted to turn on the frame below said guides, two inking rollers each having a pair of bearing blocks movable on the guides, wedge blocks adjustably mounted to coöperate with the bearing blocks of the lower roller for the purpose of adjusting said roller toward and from the feeding roller, and yielding means acting on the bearing blocks of the upper roller for the purpose of holding said upper roller toward the lower inking roller, said means comprising a weighted frame coöperating with the bearing blocks of the upper roller.

17. A ribbon inking machine comprising a frame having a pair of standards provided with guide slots, an ink feeding roller jour-

naled in the standards below said guide slot, a pair of rollers each having a pair of bearing blocks movable in the guide slot, wedge members adjustable transversely of the slots at the lower ends thereof and coöperating with the bearing blocks of the lower inking roller, a frame movably mounted on the standards coöperating with the bearing blocks of the upper inking roller, and a weight acting on said frame.

18. A ribbon inking machine comprising a frame having a pair of standards provided with guide slots, an ink feeding roller journaled in the standards below said guide slots, a pair of rollers each having a pair of bearing blocks movable in the guide slots, wedge members adjustable transversely of the slots at the lower ends thereof and coöperating with the bearing blocks of the lower inking roller, a frame movably mounted on the stands coöperating with the bearing blocks of the upper inking roller, means acting on said frame for exerting a downward pressure on said bearing blocks, and adjustable screws carried by the movable frame for coöperating with the fixed part for the purpose of equalizing the pressure on the rollers.

HENRY G. MUTSCHLER.
